UNITED STATES PATENT OFFICE.

WILLIAM MOULTON, OF ATTLEBORO, MASSACHUSETTS, ASSIGNOR TO F. W. WEAVER
AND COMPANY, OF ATTLEBORO, MASSACHUSETTS, A FIRM.

CLASP.

1,127,074.

Specification of Letters Patent.

Patented Feb. 2, 1915.

Application filed July 28, 1914. Serial No. 853,736.

To all whom it may concern:

Be it known that I, WILLIAM MOULTON, a citizen of the United States, residing at Attleboro, in the county of Bristol and State of Massachusetts, have invented certain new and useful Improvements in Clasps, of which the following is a specification.

My invention relates to that class of 10 clasps which are particularly adapted to use upon lingerie, neckties, and other parts of wearing apparel.

The essential objects of my invention are to provide a non-abrasive means in a clasp 15 for yieldingly pressing the engaged pieces of fabric into frictional contact with an adjacent portion of the clasp; to prevent slipping of clasp upon the engaged fabric; to prevent wrinkles adjacent the edges of the 20 clasp; to render an engaging means inconspicuous; to prevent cutting or defacement of the engaged fabric; and to attain these results in a structure that is inexpensive to construct, and certain and facile in operation.

To the above ends essentially my invention consists in such parts and combinations of parts as fall within the scope of the appended claim.

30 In the accompanying drawings which form a part of this specification, Figure 1 is a front elevation of my novel clasp engaged with two fabric strips, Fig. 2, a section of the same on line α , α , of Fig. 1, Fig. 35 3, a side elevation of the clasp in open position, Figs. 4 and 5 a bottom plan view and an end elevation respectively of the same in closed position, and Fig. 6, a section on line y , y , of Fig. 2, omitting the inclosed fabric.

40 Like reference characters indicate like parts throughout the views.

The clasp is formed from a continuous strip of thin, flat, resilient material, and comprises a base 1, provided with parallel 45 longitudinal slits 2, equidistant from the side edges of the base, and the strip of material 3 included between the slits 2 is stretched and bent by suitable tools, into a resilient arched portion, whose integral ends 50 are located near and equidistant from the ends of the base 1.

At one end of the base the material is provided with an open semi-circular bend 5, and the remaining material is continued to form a flat tongue 6 disposed in the plane 55 of the base and terminating in a flat hook 7. The hook 7 being resilient is adapted to overlap and frictionally engage a flat hook 9 upon the adjacent end of the base 1.

The operation of my clasp is as follows: 60

Two overlapped pieces 10 of lingerie or tie rest upon the base 1 and portion 3 of the clasp, and the tongue 6 is then manually pressed against the inclosed strips until the hook 7 overlaps and engages the hook 9, 65 whereby the parts are fastened. The pressure of the tongue 6 coöperating with the yielding pressure of the member 3 after this engagement forms a sufficiently tight engagement of the parts to prevent any movement of the clasp lengthwise of the engaged strips, and at the same time the pressure is so evenly distributed transversely of the strips as to prevent abrasion. The central 70 location of the member 3 remote from the edges of the base and tongue prevents the creation of wrinkles in the fabric adjacent the clasp, and furthermore locates the engaging means as a point not visible to the 75 casual observer.

80 The construction of the device from a single piece of metal renders the same inexpensive.

What I claim is,—

In a clasp, the combination of a base, a 85 resilient arcuate longitudinally-disposed member formed from the base and integral at its ends therewith, a hook upon the base forming an integral continuation thereof, a tongue upon the base, and a hook upon the 90 tongue and forming an integral continuation of the same, said latter hook adapted to engage, conform to and closely embrace the first named hook when in closed position.

95 In testimony whereof I have affixed my signature in presence of two witnesses.

WILLIAM MOULTON.
